UNITED STATES PATENT OFFICE.

ASA F. BATCHELDER, OF SCHENECTADY, NEW YORK, ASSIGNOR TO GENERAL ELECTRIC COMPANY, A CORPORATION OF NEW YORK.

LOCOMOTIVE OR CAR.

1,394,059.

Specification of Letters Patent.

Patented Oct. 18, 1921.

Original application filed March 21, 1918, Serial No. 223,724, now Patent No. 1,359,861, dated November 23, 1920. Divided and this application filed April 21, 1919. Serial No. 291,601.

To all whom it may concern:

Be it known that I, ASA F. BATCHELDER, a citizen of the United States, residing at Schenectady, county of Schenectady, State of New York, have invented certain new and useful Improvements in Locomotives or Cars, of which the following is a specification.

One of the most serious problems to over-
10 come in building locomotives and cars for high speed service, is the effect of the side pressure against the rails. Such side pres-
sure has a tendency to shear the spikes that hold the rails to the ties and thus spread the
15 rails. This side pressure is due to the guid-
ing of the locomotive by the track and occurs when the locomotive or car strikes a curve, special work, or irregularities in the track. It is also produced by the oscillation of the
20 trucks on track of any kind, even tangent track.

My invention relates to locomotives or cars provided with two or more trucks, at least one of which is rigidly connected to the
25 car frame, and has for its object to provide a locomotive or car in which the lateral stresses that must be applied to the rigid truck in order to guide the same will have a vertical component tending to hold the
30 outer rail to the ties, and in which a relative transverse movement between the rigid truck and car frame on the one hand and the guid-
ing truck on the other is permitted, main-
taining at the same time a predetermined
35 centering or returning effort between the car frame and the guiding truck. A further object of my invention is to reduce to a minimum the oscillation of the trucks.

The various features of novelty which
40 characterize my invention are pointed out in the claims annexed to and forming a part of this specification. For a better understand-
ing of my invention, reference may be had to the following description taken in
45 connection with the accompanying drawing, in which Figure 1 is a skeleton view of an electric locomotive embodying my invention; Fig. 2 is a side elevation of one-half of the locomotive shown in Fig. 1; Fig. 3 is a sec-
tional view taken on the line 3—3 of Fig. 2;
50 Fig. 4 is a sectional view taken on the line 4—4 of Fig. 3; Fig. 5 is a sectional view taken on the line 5—5 of Fig. 4; Fig. 6 is a view similar to that of Fig. 3 showing a

modification of the structure of that figure; 55 and Fig. 7 is a plan view of the rollers and adjacent structure of Fig. 6.

In the accompanying drawings and fol-
lowing description, I have illustrated and
described in some detail a certain cab or 60 body construction which is not claimed
herein but is disclosed and claimed in my
copending application Serial No. 223,724,
filed March 21, 1918, now Patent 1,359,861,
Nov. 23, 1920, of which the present applica- 65
tion is a division.

In accordance with one aspect of my in-
vention, the running gear of the locomotive
or car comprises two or more trucks of the
usual construction, the car frame being 70
rigidly connected to the frame of one of the
trucks and supported on the truck frame of
another of the trucks at a point above the
truck frame, said support allowing a rela-
tive transverse or angular movement between 75
the car frame and the second or guiding
truck and maintaining at the same time a
predetermined centering or returning effort
between the car frame and the guiding
truck. It is preferable that the returning 80
or centering effort be constant in value.
With such an arrangement better results
will be obtained than heretofore from the
standpoint of oscillation and from the stand-
point of flange wear, and furthermore the 85
lateral pressure exerted at the wheels of the
rigid truck for the purpose of guiding it,
will be applied at such a height that the re-
sulting vertical component tending to hold
the outer rail in place is greatly increased 90
over that heretofore contemplated. This ar-
rangement also facilitates the operation of
my locomotive on curves of short radii. I
also provide a guiding joint between the 95
rigid truck and the guiding truck which still
further tends to reduce the oscillation of this
truck.

In the drawing, I have illustrated my in-
vention applied to a locomotive comprising
two similar running gear sections 1 and 2, 100
each of which has mounted thereon two
trucks 3 and 4. The trucks 3 are rigidly con-
nected to the car frames 5 and are located
nearest the middle of the locomotive, the
trucks 4 being near the end of the locomo- 105
tive. Each of the trucks 3 are shown as hav-
ing pairs of wheels 6, the axles of which are
journaled in journal boxes 7, on which a

truck frame 8 is supported. These truck frames 8 are rigidly connected to the car frames 5. All of the wheels of these trucks 3 are shown as driving wheels, the axles being supplied with the well-known bipolar type of electric motor. Each of the trucks 4 has pairs of wheels 9, the axles of which are journaled in journal boxes 10, on which a truck frame 11 is supported. Only the two inner pairs of wheels of each of these trucks are shown as driving wheels, the pair of wheels at the end of each of these trucks which is at the end of the locomotive are shown as idle or guiding wheels.

15 Rigidly mounted on and extending above each of the truck frames 11 is a member 12. Coöperating with the member 12 is a member 13 carried by each of the car frames 5 and arranged to move transversely to the member 12. These two members form the centering device for maintaining a predetermined centering or returning effort between the car frame 5 and the guiding truck 4. The centering device may be placed at any desired height above the truck frame. In the drawing it is shown at a considerable height whereby the lateral stresses which must be applied to the rigid truck to guide the same will have a large vertical component tending to hold the outer rail to the ties. The member 13 comprises a bearing bracket 14, a bearing 15 and rollers 16 and 16¹ connected together by a shaft 17. The rollers can rotate on their shaft in the bearing 15 and at right angles to their shaft, due to the curvature of the surface of the bearing 15 and the coöperating surface of the bearing bracket 14, as clearly seen in Fig. 5. The rollers bear on the upper surface of the member 12, the shape of which may be anything desired, depending upon the required value of the forces desired for returning or centering the car frame 5 with reference to the truck 4 after the car frame has moved transversely with respect to the truck 4, or in other words, after the rollers 16 and 16¹ have moved from their central position on the upper surface of the member 12. In other words, the rollers 16 and 16¹ and the inclined surfaces of the member 12 are arranged with respect to the center line of the truck 4, so that when the locomotive or car strikes a curve, special work or irregularities in the track which displace this truck, the lateral thrust due to the displacement of this truck is only against the inclined surface on that side of the truck operating on the rail which is displacing the truck. I have illustrated the upper surface of the member 12 as V-shaped and so proportioned that it will require approximately 50 per cent. of the vertical pressure on the centering device to displace the truck 3 laterally, and this pressure will remain substantially constant for the full travel of the rollers.

A joint 18 is provided between each of the end or guiding trucks 4 and each of the rigid or middle trucks 3 for the purpose of guiding the trucks that follow. I have designed this joint so that it is capable of carrying a part of the load of the car frame 5, which permits the placing of the centering device in any position on the longitudinal center of the guiding truck. If it is displaced from the center of the truck and is placed, for instance, at the end of the truck 4 away from the truck 3 as shown in the drawings, the guiding truck is caused to carry its portion of the load of the superstructure partly through the centering device and partly through the joint 18. I also provide a guiding joint 19 between the rigid or middle trucks 4. This joint, however, does not carry any load, but is so designed as to allow vertical movement between the trucks 3. These joints 18 and 19 contain certain novel features which form the subject matter of my Patent No. 1,310,049, dated July 15, 1919.

As described above and illustrated in Fig. 1, my locomotive comprises two running gear sections, each having a rigid truck 4 and a guiding truck 3. The cab structure comprises two cab sections 20, each of which is mounted on a running gear section, and third section 21 located between the other two sections. The section 21 is preferably mounted so that the running gear is free to move angularly with reference thereto. The cab sections 20 are shown as extending over only a portion of each of the running gear sections. Such a construction of cab permits the use of a single heating plant for the locomotive which is placed in the cab section 21 and supplies heat to both of the cab sections 20 and if desired to the rest of the train hauled by the locomotive. This construction also permits the ready removal of the central section 21 together with the heating plant and the substitution of another central section, if the apparatus is out of order for any reason.

Figs. 6 and 7 illustrate a modification of the structure of Figs. 3, 4 and 5. In this present structure the support of the centering device comprises a transverse member 20 (which may or may not be an integral part of the truck frame), upper operating faces of which are provided by members 21 and 22. The upper working faces of these members 21 and 22, consists of oppositely inclined surfaces terminating in horns 25 and 26. The roller 27 coöperates with the surface 23 and the roller 24 simultaneously coöperates with the surface 24; the horns 25 and 26 are provided to limit the movement of the rollers 27 and 28 and to prevent the displacement of the rollers 27 and 28 from the members 21 and 22. The transverse member 30 carried by the car frame, 130

carries the rollers 27 and 28 as appears in Fig. 6. The transverse member 30, rollers 27 and 28, the bearings therefor, etc., comprise the member corresponding to member 13 of the structure Fig. 3. The axes of rollers 27 and 28 are disposed substantially along radii from that point about which the truck 4, on which the rollers bear, rotates, that is, the joint 18 between the truck 4 and its adjacent truck 3. In other words, the axes of these rollers are so arranged that the rollers move transversely to the surfaces 23 and 24 on the circumference of a circle, the center of which is the joint 18 between the truck 4 on which they bear and the adjacent truck 3. By this arrangement of the rollers they rotate on their supports, or rather on the surfaces 23 and 24, with a minimum sliding movement and hence with minimum wear of the rollers and the surfaces 23 and 24. Also, as appears particularly from Fig. 7, the members 21 and 22, or rather the surfaces 23 and 24 thereof, are disposed at such opposite angles that the length of each is substantially at right angles to the axis of its own roller. The operation of this structure is substantially like the operation of the structure of Fig. 3. The construction of Figs. 6 and 7 tends to hold the leading and trailing trucks in their central positions. When a blow is delivered by the leading or trailing truck against the rail head, the car frame is displaced laterally across the leading and trailing trucks. In such a sidewise displacement, the weight of the car frame rolls up on the inclined surface on that side, and thus transfers weight from one rail to the rail that is affected thereby, *i. e.*, the rail which is displacing the truck. In other words, the rollers 27 and 28 and the inclined surfaces 23 and 24 are arranged with respect to the center line of the truck 4, so that when the locomotive or car strikes a curve, special work or irregularities in the track which displace this truck, the lateral thrust due to the displacement of the truck is only against the inclined surface on that side of the truck operating on the rail which is displacing the truck. This action not only increases the holding power between the rail and tie at that point, but it also increases the time and distance during which the pressure is delivered to the rail head.

One advantage of the structure of Figs. 6 and 7 over the structure of Fig. 3 in which there is a single roller mounted at an elevated point, is that when the compression of the springs supporting the truck frame on the axle is released, the lever arm through which it acts to oscillate the car frame is shorter than where the roller is mounted at an elevated point, and, therefore, there is less oscillation of the car frame with the structure of Figs. 6 and 7. Furthermore, in the construction of Figs. 6 and 7, it is not

essential to mount the centering device above the truck frame, and in certain cases it may be sufficient to mount it below the top of the truck frame.

I desire it to be understood that my invention is not limited to the particular arrangements shown and that I aim in the appended claims to cover all modifications thereof which do not depart from the spirit and scope of my invention. 75

What I claim as new and desire to secure by Letters Patent of the United States, is:

1. In a locomotive or car, a car frame, a truck comprising axles, journal boxes for said axles, and a truck frame supported on said journal boxes, said truck frame being rigidly connected to said car frame, a second truck comprising an axle, journal boxes for said axle, and a truck frame supported on said journal boxes, means for supporting 80 said car frame on said second truck at a point above said truck frame, said means allowing a relative transverse or angular movement between said car frame and said second truck and maintaining a predetermined centering or returning effort between said car frame and said second truck, and a guiding joint between said trucks, said means for supporting said car frame on said second truck frame being so positioned that 95 said joint between said trucks carries part of the load on said car frame.

2. In a locomotive or car, a car frame, a truck comprising axles, journal boxes for said axles, and a truck frame supported on 100 said journal boxes, said truck frame being rigidly connected to said car frame, a second truck comprising an axle, journal boxes for said axle, and a truck frame supported on said journal boxes, means for supporting 105 said car frame on said second truck frame at a point above said truck frame, said means allowing a relative transverse or angular movement between said car frame and said second truck and maintaining a substantially constant centering or returning effort 110 between said car frame and said second truck, and a guiding joint between said trucks, said means for supporting said car frame on said second truck frame being so positioned that 115 said joint between said trucks carries part of the load of said car frame.

3. In a locomotive or car, a car frame, a truck comprising axles, journal boxes for 120 said axles, and a truck frame supported on said journal boxes, said truck frame being rigidly connected to said car frame, a second truck comprising axles, journal boxes for said axles, and a truck frame 125 supported on said journal boxes, and a centering device for supporting said car frame on said second truck frame comprising means rigidly mounted on said truck frame having a pair of oppositely inclined 130

surfaces and coöperating means carried by said car frame and arranged to move transversely to said first mentioned means, said inclined surfaces and coöperating means 5 being arranged with respect to the center line of said second truck, so that when the locomotive or car strikes a curve, special work or irregularities in the track which displace said second truck, the lateral thrust 10 due to the displacement of said truck is only against the inclined surface on that side of the truck operating on the rail which is displacing the truck.

4. In a locomotive or car, a car frame, a truck comprising axles, journal boxes for said axles, and a truck frame supported on said journal boxes, said truck frame being rigidly connected to said car frame, a second truck comprising an axle, journal boxes for said axle, and a truck frame supported on said journal boxes, and a centering device for supporting said car frame on said second truck frame comprising means rigidly mounted on said truck frame having a pair of oppositely inclined surfaces and coöperating means carried by said car frame and arranged to move transversely to said first mentioned means, said centering device maintaining a predetermined centering or returning effort between said car frame and said second truck, said inclined surfaces and coöperating means being arranged with respect to the center line of said second truck, so that when the locomotive or car strikes a curve, special work or irregularities in the track which displace said second truck, the lateral thrust due to the displacement of said truck is only against the inclined surface on that side of the truck operating on the rail which is displacing the truck.

5. In a locomotive or car, a car frame, a truck comprising axles, journal boxes for said axles, and a truck frame supported on said journal boxes, said truck frame being rigidly connected to said car frame, a second truck comprising axles, journal boxes for said axles, and a truck frame supported on said journal boxes, and a centering device 45 for supporting said car frame on said second truck frame comprising means rigidly mounted on said truck frame having a pair of oppositely inclined surfaces and coöperating means carried by said car frame and arranged to move transversely to said first 50 mentioned means, said centering device maintaining a substantially constant centering or returning effort between said car frame and said second truck, said inclined 55 surfaces and coöperating means being arranged with respect to the center line of said second truck, so that when the locomotive or car strikes a curve, special work or irregularities in the track which displace said 60 second truck, the lateral thrust due to the 65

displacement of said truck is only against the inclined surface on that side of the truck operating on the rail which is displacing the truck.

6. In a locomotive or car, a car frame, a truck comprising axles, journal boxes for said axles, and a truck frame supported on said journal boxes, said truck frame being rigidly connected to said car frame, a second truck comprising an axle, journal boxes for said axle, and a truck frame supported on said journal boxes, a centering device for supporting said car frame on said second truck frame comprising means rigidly mounted on said truck frame having a pair of oppositely inclined surfaces and co-operating means carried by said car frame and arranged to move transversely to said first mentioned means, said inclined surfaces and co-operating means being arranged with respect to the center line of said second truck, so that when the locomotive or car strikes a curve, special work or irregularities in the track which displace said second truck, the lateral thrust due to the displacement of said truck is only against the inclined surface on that side of the truck operating on the rail which is displacing the truck, and a guiding joint between said trucks.

7. In a locomotive or car, a car frame, a truck comprising axles, journal boxes for said axles, and a truck frame supported on said journal boxes, said truck frame being rigidly connected to said car frame, a second truck comprising an axle, journal boxes for said axle, and a truck frame supported on said journal boxes, a centering device for supporting said car frame on said second truck frame comprising means rigidly mounted on said truck frame having a pair of oppositely inclined surfaces and coöperating means carried by said car frame and arranged to move transversely to said first mentioned means, said centering device maintaining a predetermined centering or returning effort between said car frame and said second truck, said inclined surfaces and coöperating means being arranged with respect to the center line of said second truck, so that when the locomotive or car strikes a curve, special work or irregularities in the track which displace said second truck, the lateral thrust due to the displacement of said truck is only against the inclined surface on that side of the truck operating on the rail which is displacing the truck, and a guiding joint between said trucks. 120

8. In a locomotive or car, a car frame, a truck comprising axles, journal boxes for said axles, and a truck frame supported on said journal boxes, said truck frame being rigidly connected to said car frame, a second truck comprising an axle, journal boxes for said axle, and a truck frame supported on said journal boxes, a centering device for 130

supporting said car frame on said second truck frame comprising a member rigidly mounted on and extending above said truck frame and a coöperating member carried by said car frame and arranged to move transversely to said first mentioned member, and a guiding joint between said trucks, said centering device being so positioned that said joint between said trucks carries part of the 10 load of said car frame.

9. In a locomotive or car, a car frame, a truck comprising axles, journal boxes for said axles, and a truck frame supported on said journal boxes, said truck frame being rigidly connected to said car frame, a second truck comprising an axle, journal boxes for said axle, and a truck frame supported on said journal boxes, a centering device for supporting said car frame on said second truck 20 frame comprising a member rigidly mounted on and extending above said truck frame and a coöperating member carried by said car frame and arranged to move transversely to said first mentioned member, said centering device maintaining a predetermined centering or returning effort between said car frame and said second truck, and a guiding joint between said trucks, said centering device being so positioned that said joint 25 between said trucks carries part of the load of said car frame.

10. In a locomotive or car, a car frame, a truck comprising axles, journal boxes for said axles, and a truck frame supported on said journal boxes, said truck frame being rigidly connected to said car frame, a second truck comprising an axle, journal boxes for said axle, and a truck frame supported on said journal boxes, a centering device for supporting said car frame on said second truck frame comprising a member rigidly mounted on and extending above said truck frame and a coöperating member carried by said car frame and arranged to move 40 transversely to said first mentioned member, said centering device maintaining a substantially constant centering or returning effort between said car frame and said second truck, and a guiding joint between said 45 trucks, said centering device being so positioned that said joint between said trucks carries part of the load of said car frame.

11. In a locomotive or car, a car frame comprising two portions, four trucks, two of said trucks being at the ends of said locomotive and the other two being located between the other two, each of said trucks comprising an axle, journal boxes for said axle, and a truck frame supported on said 55 journal boxes, each of the truck frames of the middle trucks being rigidly connected to one of the portions of the car frames, and means for supporting each portion of said car frame on one of the truck frames of said end trucks at a point above said truck 60

frames, said means allowing a relative transverse or angular movement between said portions of the car frames and said end trucks and maintaining a predetermined centering or returning effort between said 70 car frame portions and said end trucks, and guiding joints between each two of said trucks.

12. In a locomotive or car, a car frame comprising two portions, four trucks, two of said trucks being at the ends of said locomotive and the other two being located between the other two, each of said trucks comprising an axle, journal boxes for said axle, and a truck frame supported on said 75 journal boxes, each of the truck frames of the middle trucks being rigidly connected to one of the portions of the car frames, and means for supporting each portion of said car frame on one of the truck frames of 80 said end trucks at a point above said truck frames, said means allowing a relative transverse or angular movement between said portions of the car frames and said end trucks and maintaining a predetermined 85 centering or returning effort between said car frame portions and said end trucks, and guiding joints between each two of said trucks, said means for supporting said portions of the car frames on said truck frames 90 of the end trucks being so positioned that said joints between said end and middle trucks carries part of the load of said car frames.

13. In a locomotive or car, a car frame comprising two portions, four trucks, two of said trucks being at the ends of said locomotive and the other two being located between the other two, each of said trucks comprising an axle, journal boxes for said 100 axle, and a truck frame supported on said journal boxes, each of the truck frames of the middle trucks being rigidly connected to one of the portions of the car frames, and a centering device for supporting each portion of said car frame on one of the truck frames of said end trucks comprising a member rigidly mounted on and extending above said truck frame and a coöperating member carried by the car frame and arranged to move transversely to said first mentioned member, and guiding joints between each two of said trucks.

14. In a locomotive or car, a car frame comprising two portions, four trucks, two of said trucks being at the ends of said locomotive and the other two being located between the other two, each of said trucks comprising an axle, journal boxes for said axle, and a truck frame supported on said 110 journal boxes, each of the truck frames of the middle trucks being rigidly connected to one of the portions of the car frames, and a centering device for supporting each portion of said car frame on one of the truck frames of 115 said end trucks at a point above said truck 120

frames of said end trucks comprising a member rigidly mounted on and extending above said truck frame and a coöperating member carried by the car frame and arranged to move transversely to said first mentioned member, and guiding joints between each two of said trucks, said centering devices being so positioned that said joints between said end and middle trucks 10 carry part of the load of said car frames.

15. In a locomotive or car, a car frame comprising two portions, four trucks, two of said trucks being at the ends of said locomotive and the other two being located 15 between the other two, each of said trucks comprising an axle, journal boxes for said axle, and a truck frame supported on said journal boxes, each of the truck frames of the middle trucks being rigidly connected 20 to one of the portions of the car frames, and a centering device for supporting each portion of said car frame on one of the truck frames of said end trucks comprising a member rigidly mounted on and extending 25 above said truck frame and a coöperating member carried by the car frame and arranged to move transversely to said first mentioned member, said centering devices maintaining a predetermined centering or 30 returning effort between said portions of the car frame and the end trucks, and guiding joints between each two of said trucks.

16. In a locomotive or car, a car frame comprising two portions, four trucks, two of said trucks being at the ends of said locomotive and the outer two being located between the other two, each of said trucks comprising an axle, journal boxes for said axle, and a truck frame supported on said journal boxes, each of the truck frames of the middle trucks being rigidly connected to one of the portions of the car frames, and a centering device for supporting each portion of said car frame 45 on one of the truck frames of said end trucks comprising a member rigidly mounted on and extending above said truck frame and a coöperating member carried by the car frame and arranged to move transversely to said first-mentioned member, said centering device maintaining a predetermined centering or returning effort between said portion of the car frame and the end trucks, and guiding joints between each two of said trucks, said centering devices being so positioned that said joints between said end and middle trucks carries part of the load of said car frames.

17. In a locomotive or car, a car frame comprising two portions, four trucks, two of said trucks being at the ends of said locomotives and the other two being located between the other two, each of said trucks comprising an axle, journal boxes for said axle, and a truck frame supported on said

journal boxes, each of the truck frames of the middle trucks being rigidly connected to one of the portions of the car frames, a centering device for supporting each portion of said car frame on one of the truck frames of said end trucks comprising a member rigidly mounted on and extending above said truck frame and a coöperating member carried by the car frame and arranged to move transversely to said first-mentioned member, said centering device maintaining a substantially constant centering or returning effort between said portion of the car frame and the end trucks, and guiding joints between each two of said trucks, said centering devices being so positioned that said joints between said end and middle trucks carries part of the load of said car frame.

18. In a locomotive or car, a car frame, a truck comprising axles, journal boxes for said axles, and a truck frame supported on said journal boxes, said truck frame being rigidly connected to said car frame, a second truck comprising axles, journal boxes for said axles, and a truck frame supported on said journal boxes, a guiding joint between said trucks, and a centering device for supporting said car frame on said second truck frame comprising means rigidly mounted on said truck frame and provided with two oppositely inclined surfaces and a coöperating member carried by said car frame comprising two rollers, one of said rollers coöperating with one of said inclined surfaces and the other of said rollers simultaneously coöperating with the other of said inclined surfaces.

19. In a locomotive or car, a car frame, a truck comprising axles, journal boxes for said axles and a truck frame supported on said journal boxes, said truck frame being rigidly connected to said car frame, a second truck comprising an axle, journal boxes for said axle, and a truck frame supported on said journal boxes, a guiding joint between said trucks, and a centering device for supporting said car frame on said second truck frame comprising means rigidly mounted on said truck frame and provided with two oppositely inclined surfaces and a coöperating member carried by said car frame comprising two rollers, one of said rollers coöperating with one of said inclined surfaces and the other of said rollers simultaneously coöperating with the other of said inclined surfaces, the axles of said rollers being so disposed that said rollers move on said oppositely inclined surfaces on the circumference of a circle, the center of said circle being said guiding joint.

20. In a locomotive or car, a car frame, a truck comprising axles, journal boxes for said axles, and a truck frame supported on said journal boxes, said truck frame being

- rigidly connected to said car frame, a second truck comprising an axle, journal boxes for said axle, and a truck frame supported on said journal boxes, a guiding joint between 5 said trucks, and a centering device for supporting said car frame on said second truck frame comprising a member rigidly mounted on said truck frame and a coöperating member carried by said car frame comprising 10 two rollers, the axes of said rollers being so disposed that said rollers move transversely to said first mentioned member on the circumference of a circle, the center of said circle being said guiding joint, said 15 centering device being so positioned that said joint between said trucks carries part of the load of said car frame.
21. In a locomotive or car, a car frame, a truck comprising axles, journal boxes for 20 said axles, and a truck frame supported on said journal boxes, said truck frame being rigidly connected to said car frame, a second truck comprising an axle, journal boxes for said axle, and a truck frame supported on 25 said journal boxes, a guiding joint between said trucks, and a centering device for supporting said car frame on said second truck frame comprising a member rigidly mounted on said truck frame and provided with 30 two oppositely inclined surfaces and a coöperating member carried by said car frame comprising two rollers, the axes of said rollers being so disposed that said rollers move on said oppositely inclined surfaces on 35 the circumference of a circle, the center of said circle being said guiding joint, said centering device being so positioned that said joint between said trucks carries part of the load of said car frame.
40. 22. In a locomotive or car, a car frame comprising two portions, four trucks, two of said trucks being at the ends of said locomotive and the other two being located between the other two, each of said trucks comprising an axle, journal boxes for said 45 axle, and a truck frame supported on said
- journal boxes, each of the truck frames of the middle trucks being rigidly connected to one of the portions of the car frames, guiding joints between each two of said trucks, and a centering device for supporting each portion of said car frame on one of the truck frames of said end trucks comprising a member rigidly mounted on said truck frame and a coöperating member carried by the car frame comprising two rollers, the axes of said rollers being so disposed that said rollers move transversely to said first mentioned member on the circumference of a circle, the center of said circle being the guiding joint between the truck on which said first mentioned member of the centering device is mounted and the adjacent truck. 55
23. In a locomotive or car, a car frame comprising two portions, four trucks, two of said trucks being at the ends of said locomotive and the other two being located between the other two, each of said trucks comprising an axle, journal boxes for said 60 axle, and a truck frame supported on said journal boxes, each of the truck frames of the middle trucks being rigidly connected to one of the portions of the car frames, guiding joints between each two of said trucks, and a centering device for supporting each portion of said car frame on one of the truck frames of said end trucks comprising a member rigidly mounted on said truck frame and having oppositely inclined surfaces and a coöperating member carried by the car frame comprising two rollers, the axes of said rollers being so disposed that said rollers move on said oppositely inclined surfaces on the circumference of a circle, the center of said circle being the guiding joint between the truck on which said first mentioned member of the centering device is mounted and the adjacent truck. 65
- In witness whereof, I have hereunto set my hand this 16th day of April, 1919.
- ASA F. BATCHELDER.
